UNITED STATES PATENT OFFICE.

ROBERT T. FRAZIER, DONALD W. BODDY, AND CURTIS F. HAMLIN, OF CHATTANOOGA, TENNESSEE, ASSIGNORS TO TENNESSEE FURNITURE CORPORATION, OF CHATTANOOGA, TENNESSEE, A CORPORATION OF TENNESSEE.

REFRIGERATOR.

Application filed June 17, 1925. Serial No. 37,716.

To all whom it may concern:

Be it known that we, ROBERT T. FRAZIER, DONALD W. BODDY, and CURTIS F. HAMLIN, citizens of the United States, residing at 5 Chattanooga, in the county of Hamilton and State of Tennessee, have invented certain new and useful Improvements in Refrigerators; and we hereby declare that the following is a full, clear, and exact description thereof, reference being had to the accompanying drawings, which form part of this specification.

Our invention relates to refrigerators of the so called porcelain covered type. The 15 object of the invention is to provide a novel, simple practical refrigerator of such type which will be simpler in construction, superior in durability, and of enhanced refrigerating ability.

20 The complete refrigerator constructed in accordance with our invention comprises an assembled structural steel frame, enclosing an interior insulated container element, and supporting an exterior casing. The preferred form of such refrigerator comprises three major elements to wit: (1) a container or containers enclosed in an insulated casing forming a single unit; (2) a structural steel supporting frame; and (3) an 25 exterior casing attached to and enclosing the said frame.

Heretofore refrigerators have been made with porcelain linings and covered with porcelain on the exterior. In most cases the 35 exterior porcelain was held in place by nickeled strips on the corners, either angles or a combination of an angle and a three-quarter tube; and while these refrigerators, when first made are attractive in appearance 40 in the practical use thereof various practical defects and objections have developed.

Heretofore the best of such refrigerators composed a wooden case lined with porcelain, and covered with porcelain enameled 45 iron plates secured to the outside of the wooden case. In warm humid weather the porcelain exterior plates "sweat" on the inside, and the moisture is absorbed by the wood frame causing the same to swell, and 50 force out the screws that hold the corner

strips in place and dislocating and rupturing the refrigerator in places.

Another object of our invention is to make a refrigerator which will not be subject to such defects or objections in use.

To enable others to fully understand and use our invention we will explain one embodiment thereof as illustrated in the accompanying drawings, and summarize in the claims the essentials of the invention and 55 novel features of construction and novel combinations of parts for which protection is desired. In said drawings:

Figure 1 is a perspective view of a refrigerator with the doors removed and 60 broken away in parts to show the interior construction.

Figure 2 is a vertical section through the refrigerator on the line 2—2, Figure 3.

Figure 3 is a transverse section on the 70 line 3—3, Figure 2.

Figure 4 is a detail.

Referring to the drawings the main features of the refrigerator shown are an L-shaped porcelain food container, a rectangular ice container, an insulating covering enclosing the containers; a metallic skeleton supporting frame; and an exterior protective casing. The L-shaped container has a flue punched through its left hand upper 75 wall communicating with the ice chamber, and a second flue punched through the top of the L, which communicates with the bottom of the ice chamber. The ice container is also welded in one piece and provided with 80 flues registering with the flues in the container, before mentioned.

The food container 1 is preferably made in L-shape and of one piece either of iron porcelain lined, or enameled or of porcelain, 85 as usual. The rectangular container 2 forming the ice chamber is also preferably made of iron porcelain lined or enameled. These two containers are placed in position as shown with the container 2 resting on 90 the L of the container 1, the openings or flues in the two containers registering as shown at 1^a and 2^a. The two containers are then cemented together as usual, and are 95 then enclosed by an insulating covering. 100

applied to the top, bottom, sides and back of the containers, as indicated in Figs. 2 and 3, such insulating covering being preferably made of the usual one and one-half inch insulation or cork board. Obviously the food and ice compartments might be made in one casting, or could be otherwise formed, within the scope of the invention.

The united and insulated containers, as described, are then mounted in a skeleton metallic supporting frame; which frame preferably comprises corner angle-iron uprights 4^a. The two adjacent end angle iron uprights are preferably connected at top by 10 an angle-iron bar 4^b, and at bottom by an angle iron bar 4^d, and also by intermediate angle iron bars 4^e to form a stiff substantial frame. The two front uprights 4^a are further connected by the transversely disposed 15 angle-iron bars 4^f at bottom and 4^g at top. The two rear uprights 4^a are also further connected by transverse angle iron bars 4^h at top and 4^k at bottom, and may be also connected by intermediate angle iron bars 20 like 4^e.

The bottom angle iron bars 4^k and 4^f may be connected by transverse angle iron bars 4ⁱ; and the top angle-iron bars 4^g and 4^h may be connected by transverse angle iron 25 bars 4^m. The several angle iron bars or members forming the complete skeleton frame may be partially assembled and suitably fastened together, so that sections of the supporting frame can be readily placed 30 around and applied to the containers, to securely position the same within the supporting frame, as indicated in the drawings.

The said skeleton metal frame encloses the top, bottom, both ends and back of the 40 container. To the front side of this skeleton frame (at the open front side of the containers) is preferably attached a wooden frame 8 which is preferably composed of three layers of wood as shown, and is 45 suitably fastened to the skeleton steel frame members; said front frame 8 is provided with openings to permit access to the ice chamber, the main provision chamber and the smaller provision chamber beneath the 50 ice chamber, as usual. The said openings are closable by suitable doors (not shown) which may be suitably hinged to the wooden frame and held closed by the usual fasteners, not shown.

The skeleton metal frame also supports an exterior casing which may be of metal or wood; but preferably comprises wooden side members 5; covered by metal side members 6, which latter may be porcelain enamelled. To the front of the wooden frame 8 may be secured porcelain-covered metal plates 8^a, 8^b as indicated in the drawings. The back 5^a may be covered with galvanized iron plate 6^b. If desired a wall board or metal bottom plate 7 may be attached to the

bottom of the skeleton frame. The top may be covered by a wall board plate 12^a covered by a metal cap plate 12. The process of construction is preferably as follows:

When the parts 1 and 2 are registered in 70 position, 1½ inch boards of cork are cemented to the outside thereof preferably by means of hydrolene, a tarry hydrocarbon. This holds the containers in place, and forms with the containers a single 75 homogeneous interior of rectangular shape.

The light angle iron members are formed into end frames as described and may be provided with suitable truss bracing. The back frame and the bottom frame are constructed in like manner; suitable gusset plates and corner braces provided with holes for bolts may be welded to the several frames in such manner that they may be easily bolted together to form a rigid 80 metallic frame structure to enclose and support the interior rectangular cork covered containers.

The outer casing of ordinary wall board can then be attached to the frame and over 90 this is applied the outer porcelain or enameled steel or metal plates forming the exterior casing.

The ordinary wooden front frame made in the usual form and provided with the 95 necessary facing strips similar to the ordinary front is then securely bolted to the front of the skeleton frame. The exterior enameled iron sheets are then applied to the wooden frames, said sheets made in metal 100 formed to extend from in the rear over the ends and to cover the front stiles up to the door openings. The filling strips are then applied and held in place by nails and screws passing through the said strips into 105 the wooden front frame. Then the top plate 12 made in the shape of a pan with flanges is fitted over the whole and screwed or bolted in place.

The doors (not shown) would be made 110 as usual with a basic wooden frame carrying the same cork insulation on the inside, backed up with a porcelain lining and covered on the exterior with porcelain pans 115 held in place with suitable screws, nails or bolts.

The upper corners around the top and the bottom edge of the exterior enameled iron sheets forming the case are what is termed 120 in the trade "black wiped"; that is to say, in the process of enameling all of the white enamel for a space of $\frac{7}{8}$ of an inch on each side of the corner is cleaned off and then over this cleaned space a black enamel is 125 applied giving the refrigerator an extremely neat appearance of brilliant white, edged with a rather narrow black striping. In addition to the enhanced ornamental appearance the purpose of the black is to prevent chipping or cracking, since the basic 130

element in the black enamel is manganese oxide which produces an extremely tough coating, whereas the basic element of color in the white is tin oxide, which produces a 5 rather brittle coating.

It will be seen that our refrigerator has a complete skeleton metal supporting frame, instead of a wooden supporting frame, and on the inside and outside of this 10 skeleton frame are applied porcelain enamel iron plates; and the interior and exterior members, together with the insulation is sustained by the structural steel skeleton frame.

15 The usual removable ice pan 13 is shown in the bottom of the ice chamber and is not a part of the present invention.

This refrigerator can be easily crated by means of special bolts 9 (see Figs. 2 and 3) 20 which can be affixed to the four corners of the bottom of the refrigerator in place of the casters. These bolts are then passed through 2x4 members 10 of a rigid cross-braced crate frame (not shown) and securely fastened by suitable washers and nuts 9^a, 9^b on both sides of the frame members 10. These bolts do not touch the exterior porcelain enamel surface, but are fastened directly to the structural steel frame in the 25 walls. As a further means of holding the refrigerator securely in the crate bolts 11 (see Figs. 3 and 4) may be tapped through members 10^a of the crate and screwed into the nuts 11^c welded to the inside of one of 30 the angle irons 4^m at the back of the main skeleton frame said bolts being secured by nuts 11^b and 11^c on opposite sides of the crate member 10^a. The whole crate is not shown but the manner of crating the refrigerator 35 will be readily understood from the foregoing, and it is obvious that when the refrigerator is thus crated any shocks in transportation sustained by the crate do not injure the porcelain enameled exterior of the refrigerator, but pass directly into and are absorbed by the structural frame work inside 40 thereof. By this method the crate is attached to the main supporting metal frame of the refrigerator as above described, and 45 the connecting elements between the said crate and the said frame pass through the third element or exterior case of the refrigerator. This method is different from the common practice in crating refrigerators or 50 other manufactures having exteriors which can be easily damaged. This method of crating makes it possible to ship the refrigerators with safety, because all of the shocks or strains received by the crate in shipment 55 do not affect the perishable exterior but are carried directly to the shock absorbing interior structure.

We claim:

1. A refrigerator comprising a skeleton 60 supporting frame having angular uprights

and metal bars connecting said uprights; a food and ice container mounted in and supported by said frame; an insulated lining covering the back, sides, top and bottom of said container; said container and frame 70 having openings in their fronts to permit access to the container; an exterior casing mounted on said skeleton frame and supported thereby; and a wooden frame attached to the front of the skeleton frame and 75 having doors therein opposite the openings in the container.

2. In a refrigerator as set forth in claim 1, the container comprising an L-shaped food container and a rectangular ice container mounted upon the L-shaped container and enclosed within the said insulated lining. 80

3. A refrigerator as set forth in claim 1, having porcelain covered metal plates 85 mounted on the exterior of the said casing.

4. A refrigerator comprising a skeleton metal supporting frame; an interior food and ice container mounted in said frame; an insulating lining covering the back, sides, 90 top and bottom of said container; an exterior casing mounted upon and enclosing said skeleton frame; and a wooden frame attached to the front of the said metal frame and having openings registering with the 95 openings in the ice and food compartments.

5. In a refrigerator as set forth in claim 4, the container comprising an L-shaped food container and a rectangular ice container 100 mounted upon the L-shaped container and enclosed within the said insulated lining.

6. In a refrigerator as set forth in claim 4, the outer casing including exterior porcelain covered metal plates. 105

7. A refrigerator as set forth in claim 4 having porcelain covered metal plates covering the top and sides of the said casing and front of said wooden frame. 110

8. A refrigerator comprising a skeleton metal supporting frame; an interior food and ice container mounted in said frame and having openings for doors in its front; an insulating lining covering the back, sides, 115 top and bottom of said container; an exterior casing mounted upon and enclosing said skeleton frame; and a wooden frame attached to the front of the said metal frame and having openings registering with the openings in the ice and food compartments, 120 substantially as described.

9. In a refrigerator as set forth in claim 8, the container comprising an L-shaped food container and a rectangular ice container mounted upon the L-shaped container and 125 enclosed within the said insulated lining.

10. A refrigerator as set forth in claim 8, having porcelain covered metal plates covering the top and sides of the said casing and front of said wooden frame. 130

11. A refrigerator comprising a skeleton supporting frame having angular uprights and metal bars connecting said uprights; a food and ice container mounted in and supported by said frame; said container and frame having openings in their fronts to permit access to the container and adapted to be closed by suitable doors; and an exterior casing mounted on said skeleton frame and supported thereby; and a wooden frame attached to the front of the said metal frame and having openings registering with the openings in the ice and food compartments. 10
12. In a refrigerator as set forth in claim 11, the container comprising an L-shaped food container and a rectangular ice container mounted upon the L-shaped container and enclosed within the said insulated lining. 15
13. A refrigerator as set forth in claim 11 having porcelain covered metal plates covering the top and sides of the said casing and front of said wooden frame. 20
14. A refrigerator comprising a skeleton supporting frame having angular uprights and metal bars connecting said uprights at ends, front, back, sides, top and bottom; a food and ice container mounted within and supported by said frame; an insulated lining covering the top, bottom, sides and back of said container; said container having openings in its front to permit access thereto; an exterior casing mounted on said skeleton frame and supported thereby; and a wooden frame attached to the front of the said metal frame and having openings registering with the openings in the ice and food compartments. 25
15. A refrigerator comprising a skeleton supporting frame having angular uprights

and metal bars connecting said uprights; a food and ice container mounted in and supported by said frame; an insulated lining covering the top, bottom, sides and back of said container; said container and frame having openings in their fronts to permit access to the container and adapted to be closed by suitable doors; and an exterior casing mounted on said skeleton frame and supported thereby; and a wooden frame attached to the front of the said metal frame and having openings registering with the openings in the ice and food compartments; and metal plates covering the top and sides of the skeleton frame and the front side of said wooden frame. 45

16. A refrigerator comprising a skeleton supporting frame having angular uprights and metal bars connecting said uprights at the ends, front, back, sides, top and bottom thereof; a food and ice container mounted within and supported by said frame, and having openings in its front to permit access thereto; an insulated covering mounted in said compartment covering the top, bottom, sides and back thereof; an exterior casing mounted on said skeleton frame and supported thereby; a wooden frame attached to the front of the said skeleton frame and having openings registering with the openings in the ice and food compartments; and porcelain metal plates covering the top and sides of the skeleton frame and the front side of said wooden frame. 60

In testimony that we claim the foregoing as our own, we affix our signatures.

ROBERT T. FRAZIER.
DONALD W. BODDY.
CURTIS F. HAMLIN.
